UNITED STATES PATENT OFFICE

LOUIS LUMIÈRE, OF NEUILLY-SUR-SEINE, FRANCE

ACOUSTIC DIAPHRAGM MADE OF WARPED ELEMENTARY SURFACES WITH PARALLEL EDGES

Application filed May 13, 1930, Serial No. 452,008, and in France June 4, 1929.

My invention relates to an acoustic diaphragm, square or rectangular in shape, made of warped trapezoidal elementary surfaces having parallel edges. Such a diaphragm **5** has the advantage of possessing the rigidity that is necessary for obtaining a high acoustic efficiency.

The invention will be illustrated in the following drawings, in which:—

10 Figure 1 is a plan view of a paper ring with lines traced on it, said paper ring serving to make the acoustic diaphragm.

Figure 2 shows a part of said paper ring unfolded, after it has been plaited and cut **15** along one radius, the edge of the inside circumference being developed along a straight line as it will be explained hereafter.

Figure 3 is a transverse section on the line **20** *x*—*x* of Figure 2 of an element consisting of a part of a ring.

Figure 4 is an end view corresponding to Figure 3.

Figures 5 and 6 are respectively an elevation and a transverse section of an acoustic **25** diaphragm obtained by assembling together two parts of a ring similar to that of Figure 2.

Figure 7 is a sectional view showing how **30** some points of the edge of the diaphragm are secured to the frame through cork or felt washers.

Figures 8, 9 and 10 show, on a larger scale, the middle part of the diaphragm thus obtained, in the vicinity of the plaited edges which are assembled together.

35 Figures 11 to 14 relate to different forms of the diaphragm.

The acoustic diaphragm, according to my invention, is made of trapezoidal elementary surfaces *a*, Figure 1, limited by equidistant **40** radii of a ring, the proportions of the inner and outer diameter of which may vary according to the warping conditions which give the necessary rigidity to the elements, when the latter have been folded and developed. Said elementary surfaces are next **45** folded, and the ring is cut into parts, which are developed in such a manner that the inner circumference of said parts is disposed along a straight line. The length of said line depends on the dimensions of the diaphragm.

The parts of rings thus developed are, in horizontal projection, rectangular in shape, and the edges of the folds, on account of the warping that they are given, are slightly bent.

The relative dimensions of the inner and outer diameters of the ring may, for instance, be chosen in the proportion of 1 to 2, and in that case, the folds, on the side of the larger bases of the trapezoidal elements, are at an angle of 60° to each other.

In order to obtain the acoustic diaphragm, two elements such as the one shown in Figures 2, 3 and 4 are assembled by placing them side by side, so that the folded large bases overlap each other, as it is shown on a larger scale in Figures 8 and 9; and said overlapping parts are glued together. The common glued part is then pierced through, so as to enable to insert, in a direction perpendicular to the edges, a rigid bar *b*, made of aluminium, wood or any other material, thin and rather wide, which is stuck to the folded elements by means of small paper bands or better of a cellulosic varnish.

It is through said bar, which is driven by its middle part, or by any other part, that the diaphragm is connected to the movable rod of an acoustic or electromagnetic vibrator.

75 Said acoustic diaphragm may be mounted in a frame *c* made of wood or any suitable material, and fixed in position through cork or felt washers *d* which hold its straight edges in suitable points, so as to avoid any parasitic vibration.

80 Said diaphragm may be made of drawing paper, which subsequently, will be coated or not with a suitable varnish or any other material. It is also possible to use, for making the diaphragm, a very thin laminated sheet of aluminium, about 0.01 millimeter thick, or a sheet of any other similar light metal or alloy, lined with a sheet of a suitable paper, weighting, for instance 120 grammes by **85** square meter, or of any other suitable substance.

90 When the diaphragm according to the invention is made with a very thin laminated sheet of metal, lined with paper, a very good **95** 100

rigidity is obtained, which causes all the points of the surface to vibrate in phase.

Instead of using a rod for connecting together the diaphragm elements, as shown in Figures 5, 6, 8 and 9, one may use a tube of light metal or any other suitable material, passing through the folds of the diaphragm, in the same way as the rod.

Figures 11 and 12 show this embodiment of the invention.

In these figures, the parts of rings are placed in the same way as above; their folds slightly overlap each other, and are glued together; they are connected together by means of a tube b_1 , made of a light metal, or any other material, which passes through the folds. As explained above said tube is actuated by the vibrations of the motor and transmits said vibrations to the diaphragm.

Instead of actuating the rod or tube b or b_1 by a single motor, it may be advantageous to actuate said rod or tube by several motors connected to several points of the rod or tube.

For this purpose, said points will be so distributed along the rod or tube as to set in vibration parts of the diaphragm having equal areas. For instance, in the case of Figure 13, rod b is actuated in two points A and B, which set in vibration, parallelly, equal areas l and m , as indicated, in dotted lines, by their diagonals, and in the case of Figure 14, rod b is actuated in three points A, B, C, which set in vibration equal areas l , m , n . Of course such points could be still multiplied.

While I have disclosed preferred forms of my invention, I do not wish to be limited thereto, as there might be changes made in the construction, disposition and form of the parts without departing from the spirit of my invention, as comprehended within the scope of the appended claims.

What I claim is:

1. A method for obtaining an acoustic diaphragm which consists in taking a ring of a thin material, in folding said ring along equidistant radii, in cutting it into elements of given length, in unfolding said elements so that their side corresponding to the inner circumference of the ring is applied along a straight line and the edges of their folds are all parallel, in applying two such elements one against the other along their folded bases so that they slightly overlap each other and in gluing them together, in passing through all the folds of the overlapping part a rigid piece and in fixing said piece to the folds, so that said rigid piece serves to transmit the vibrations to the diaphragm.

2. A rectangular acoustic diaphragm comprising two folded elements having each a straight side and a folded side and edges of folds parallel between themselves, means for securing together the folded sides of said elements, a rigid piece passing through the folds of both elements, means for fixing said

piece to the elements, washers for holding the straight sides of the elements and a frame for supporting said washers.

3. A rectangular acoustic diaphragm comprising two folded elements made of a thin material having each a straight side and a folded side and edges of folds parallel between themselves, means for securing together the folded sides of said elements, a metallic tube passing through the folds of both elements whereby the vibrations are transmitted to the diaphragm, means for fixing said tube to the elements, washers for holding the straight sides of the elements, and a frame for supporting said washers. 70 75 80

4. A rectangular acoustic diaphragm comprising two folded elements made of laminated aluminium having each a straight side and a folded side and edges of their folds parallel to one another, means for securing together the folded sides of said elements, a metallic tube passing through the folds of both elements whereby the vibrations are transmitted to the diaphragm, means for fixing said tube to the elements, washers for holding the straight sides of the elements, and a frame for supporting said washers. 85 90 95

5. A rectangular acoustic diaphragm comprising two folded elements made of laminated aluminium having each a straight side and a folded side and the edges of their folds parallel to one another, means for securing together the folded sides of said elements, a metallic tube passing through the folds of both elements and adapted to be set in vibration in several points, means for fixing said tube to the elements, cork washers for holding the straight sides of the elements, and a frame for supporting said washers. 100 105 110

6. A rectangular acoustic diaphragm comprising two folded elements made of laminated aluminium having each a straight side and a folded side and edges of their folds parallel to one another, a paper lining on each folded element, means for securing together the folded sides of said elements, a metallic tube passing through the folds of both elements whereby the vibrations are transmitted to the diaphragm, means for fixing said tube to the elements, washers for holding the straight sides of the elements, and a frame for supporting said washers. 115 120 125

In testimony whereof I have signed this specification.

LOUIS LUMIÈRE.
